MEANS FOR SPLICING ELECTRICAL CONDUCTORS

Thomas A. Sanders, Philadelphia, Pa.

Application November 20, 1945, Serial No. 629,873

4 Claims. (Cl. 287—78)

1

This invention relates to splicing electric conductors, and more specifically, to splices made with pressed connectors.

Heretofore, sleeve connectors of the compression type for splicing electric conductors have used a cylindrical sleeve in which two aligned single conductors are disposed butt toward butt. In these splices, at least two indentations are made for each conductor, and the sleeves are accordingly made long enough for at least four indentations. The resulting splice is therefore excessive in length with consequent waste of labor, tape and space. Furthermore, the connectors and compression tools presently available are not designed to unite more than two conductors in a single splice.

One of the principal objects of my invention is to provide a compression splice of greatly reduced length.

Another object of the invention is to provide a multiple compression splice, i. e. one in which two or more conductors are joined with one or more additional conductors by means of a single connector.

A further object of my invention is to provide a generally oblong compression sleeve of conducting metal.

Still another object of the invention is to provide an indenting tool capable of producing a strong permanent compression splice of good electrical conductivity.

With these and other objects in view which will become apparent from the ensuing description and claims, the following sets forth the details of construction and combination of parts of a specific embodiment of my invention which I illustrate as an example, and which will best be understood when read in conjunction with the accompanying drawing, in which

Fig. 1 is a fragmentary view, partly in section, showing two conductors spliced according to my invention.

Fig. 2 is a view of my splice showing two conductors of equal size connected to a conductor of larger size.

Fig. 3 is a diagrammatic transverse sectional view illustrating the conductor ends of the splice of Fig. 2 in assembly position before compressing.

Fig. 4 is a section on the line 4—4 of Fig. 2 showing the indentations in one conductor and the sleeve.

Fig. 5 is a view showing the splice of my invention used to connect four conductors.

Fig. 6 is a section on the line 6—6 of Fig. 5 illustrating the condition of the conductors within the sleeve indentation.

Fig. 7 is a transverse sectional view of the splice of Fig. 5 illustrating the conductor ends in assembly position within the sleeve before compressing.

2

Fig. 8 is a fragmentary view of the compression tool showing the stepped contour of the jaws.

Fig. 9 is a fragmentary sectional view showing the position of the tool jaws with respect to the sleeve and conductor end assembly, while making the indentation.

Referring to the drawing, Fig. 1 shows the ends 10, 10 of solid conductors from which the insulation has been stripped, positioned adjacent and parallel to each other in lapped relation. A sleeve 11 of ductile metal of good electric conductivity, such as copper, of generally oblong shape, encircles the lapped ends 10. Two transverse indentations 12 are formed in the flat of the sleeve 11 and two indentations 13 are formed in the ends 10 by the jaws 14 and 15 of a compression tool 16.

Fig. 2 shows a multiple splice 20 comprising the ends 21, 21 of conductors of equal size connected to the end 22 of a third conductor of larger gage within a sleeve 23, with transverse primary indentations 24. The sleeve 23 is of such dimensions relative to the row of conductor ends 21, 21, and 22 that, before compression, said ends fit easily in the sleeve without excessive looseness, as illustrated in Fig. 3.

Fig. 8 illustrates the shape of jaws 14 and 15 of the compression tool 16 which is arranged for power operation or hand operation by compound leverage (not illustrated) of the usual type well known in the art. The lower jaw 14 is stepped transversely to provide a primary indenter 32 of rectangular shape and a secondary indenter 33 of similar shape positioned adjacently thereto but recessed below the indenter 32. The upper jaw 15 has indenters 34 and 35 complementary to indenters 32 and 33 and the tool 16 is constructed so that the indenters are in parallel planes when the jaws are in final closed position, as illustrated. Positioned inwardly of the indenters 32 and 34 are similarly shaped indenters of wider final separation for indenting a large size of sleeve. The indenters are of sufficient length to span the full width of the widest sleeve intended to be used.

Fig. 4 is a longitudinal section of part of the splice 20, showing the primary indentations 24, made by the indenters 32 and 34, and secondary indentations 25 made by the indenters 33 and 35. The position of the tool 16 in making the indentations 24 and 25 is shown in Fig. 9. The tool is placed on the sleeve 23 to one side of the center with the secondary indenters 33 and 35 toward the end of the sleeve and with the jaws either flush with the end of the sleeve or set back from the end as illustrated.

For any combination of conductors and sleeve there is an optimum compression of the primary indenters which will cause plastic flow of the metals of conductors and sleeve under these in-

denters into a solid metallic mass to give maximum tightness and permanence of the splice without overstraining the metals. The tool 16 is so designed that on completion of compression there is a predetermined spacing of the jaws to give this result. The tool 16 is provided with two sets of indenters giving optimum closure spacings for two different sleeve sizes. Additional tools may be provided for as many sleeve sizes as desired.

The function of the secondary indenters is to restrain the tendency of the outer or end portion of the sleeve to bell outward while the deep indentation is being impressed by the primary indenters. I have found it desirable to space the secondary indenters so that they make a relatively light indentation 25 which provides sufficient mechanical restraint against transverse movement of the conductors within the sleeve which might otherwise tend to loosen or break off the conductors under the primary indentation 24. In an obvious manner primary and secondary indentations are simultaneously formed with each operation of the compression tool 16.

Though I have illustrated each of the secondary indentations 25, formed by the indenters 33 and 35, as being sharply stepped from the primary indentation, it is obvious that the transition from the primary to the secondary indentation need not necessarily be abrupt, but instead may be a gradual transition of any desired curvature. Also, the secondary indentations are illustrated as being flat and lying in a longitudinal plane. However, it is readily apparent that the desired purpose would also be effectively accomplished if the secondary indentation were gradually sloped or curved to decreasing depth away from the primary indentation. Furthermore, it is within the scope of my invention to provide a secondary indentation on either side of the primary indentation instead of to one side only as illustrated. This is accomplished either by reversing the tool 16 and reindenting with registration of the primary indenter in the primary indentation, or by providing indenting jaws having appropriate secondary indenters on either side of the primary indenters instead of on one side only.

Fig. 5 illustrates a multiple splice of the ends 40, 40 of four conductors of equal size in a sleeve 50 41 with three primary indentations 42, 42. In this case the secondary indentations associated with the outer primary indentations are toward the ends of the sleeve 41. The secondary indentation associated with the middle primary indentation may be toward either end.

Fig. 7 shows the conductor ends 40 arranged in assembly position with a relatively loose fit within the oval sleeve 41. A transverse section of one of the primary indentations 42 is shown in Fig. 6, illustrating the manner in which plastic flow of the conductor metal eliminates the interstices between the conductors and sleeve.

Although I have shown my splices connecting solid conductors, which are rod-like in the sense that they are generally cylindrical, it is to be understood that my invention may be used to make equally effective splices of stranded rod-like conductors, or of solid and stranded conductors. Furthermore, it is within the scope of my invention to have as many of the conductors as desired, even all of them, inserted in the sleeve from the same end.

Also, it is evident that as many conductors as desired may be connected together in a single

splice, by this method. For example, effective splices have been made uniting six single or stranded conductors in one sleeve. With proper proportioning of sleeve sizes and thicknesses, even 5 more conductors may be connected by a single sleeve.

It is apparent that my invention, which features the conductor ends in lapped relation, has the advantage over compression splices in which the conductor ends are butted within a sleeve, in that my splice is only half as long for the same strength and effectiveness. This is often of considerable importance where space is at a premium.

It will be obvious to those skilled in the art to which the invention relates that modifications may be made in details of construction and arrangement and in matters of mere form without departing from the spirit of the invention.

I claim:

1. The method of splicing rod-like electrical conductors which comprises juxtaposing the ends of separate conductors in parallel, side by side, overlapping relation to each other in a row with 15 in an encircling metal sleeve initially of generally oblong transverse shape, and compressing the flats of said sleeve between transverse opposed indenters, bringing said flats into closer, substantially parallel, relation to each other until 20 the sleeve and conductor ends therein are deformed between the indenters into a solid metallic mass.

2. In joining rod-like electrical conductors or the like by affixing an encircling sleeve of generally oblong transverse shape of ductile metal to the members to be joined, the method which comprises assembling the ends of separate conductors within the sleeve in parallel, side by side, overlapping relation to each other in a row with 25 in said encircling sleeve, and forming opposing transverse substantially parallel flat indentations across the flats of said sleeve, with incidental deformation of the conductor ends into a solid metallic mass filling the interstices between the sleeve and conductors.

3. In joining rod-like electrical conductors or the like by affixing an encircling sleeve initially of generally oblong transverse shape of ductile metal to the members to be joined, the method which comprises assembling the ends of separate conductors within the sleeve in parallel, side by side, overlapping relation to each other in a row encircled by said sleeve, and forming across the 30 flat of said sleeve in a single operation a primary transverse flat indentation and a secondary flat indentation adjacent and parallel thereto, the primary indentation being relatively deep and deforming the sleeve and conductors therein into a solid metallic mass, and the secondary indentation being relatively shallow and providing sufficient compression of the conductors to restrain transverse movement thereof relative to the sleeve.

4. In a multiconductor splice for ductile wires and cables, the combination of a multiplicity of separate rod-like conducting members and a sleeve of generally oblong transverse shape, said conducting members being assembled parallel to each other in side by side overlapping relation in a row encircled by said sleeve and extending therethrough, and said sleeve having transverse parallel flat indentations impressed across the opposed flats of the sleeve and bridging the row 40 of conducting members and corresponding trans-

verse flat parallel indentations formed in said conducting members.
